GAS-BURNING LAUNDRY STOVE.

Application filed August 18, 1924. Serial No. 732,596.

This invention relates to a stove that is designed to be moved about from place to place as may be desired and to be conveniently cared for when not required for use, 5 the invention having reference more particularly to a gas-burning stove of the type that is especially adapted for heating water in wash-boilers and for various other purposes.

An object of the invention is to provide 10 a stove that may be quickly set up for use, more particularly for domestic purposes, to efficiently and economically supply heat at such times as may be required, and which may be readily removed and stored so as to 15 be in good condition for immediate use when again needed.

Another object is to provide a laundry 20 stove which shall be adapted for use in houses, or on porches or in yards in summer seasons and not be liable to suffer injury because of inclement weather conditions, but which shall be so constructed as to be adapted to be quickly and conveniently removed from place and hung up on a hook 25 or nail which may be secured to a wall.

A further object is to provide an improved 30 laundry stove that shall permit of being constructed entirely of such material as is not liable to be broken when the stove is roughly used or handled, and which shall permit of 35 light-weight but stiff structure and of such material as may be cheaply obtained from merchant stocks of metals, and which shall be durable and economical in use.

With the above-mentioned and other objects in view, the invention consists in a skeleton-like portable gas-burning stove having improved construction generally and particularly as to details, for obtaining improved 40 results in practical use; the invention consisting also in the novel parts or features and in the combinations and arrangements of parts as hereinafter particularly described and claimed.

Referring to the drawings, — Figure 1 is 45 a top plan of the improved stove constructed substantially in accordance with the invention; Fig. 2 is a longitudinal sectional elevation approximately centrally of the main structure thereof; Fig. 3 is a transverse 50 sectional elevation, and Fig. 4 is a perspective view of one of the parts of the stove on a reduced scale.

Similar reference characters in the different figures of the drawings indicate cor-

responding elements or features of construction herein referred to.

The improved stove comprises an oblong frame which is composed of L-section angle iron and having longitudinal top plates 1 and 2 and transverse top plates 3 and 4, all connected together with slightly curved corners, the longitudinal plates having vertical plates 5 and 6 extending downward from the outer edges thereof, the transverse plates 60 having vertical plates 7 and 8 extending downwards from the outer edge thereof to constitute stiffening members and also facing plates. The stove is provided with four short legs 9, 9' secured to the corner portions of the frame, each leg being composed of L-section iron and suitably shaped so that the upper portions closely fit against the inner sides of the vertical plates of the frame to which the legs are rigidly secured, 65 preferably by means of bolts and so that the top plates shall rest directly upon the tops of the legs. One of the transverse members of the frame supports two hangers 70 10 and 11 and the opposite transverse member supports a hanger member 12, each hanger being connected to the top plate of the member by means of a head plate 13 on the top of the main portion of the hanger. The plan dimensions of the frame correspond 75 approximately to that of a conventional wash-boiler, or may be slightly longer and broader, externally.

The stove comprises also a metallic pan 80 consisting of a bottom plate 14 and a continuous side wall 15 thereon, the top of the wall having a flange 16 which preferably extends inwardly and has bolt holes 17 therein. The pan is of such length and width that the wall thereof may be located 85 in contact with the under side of the top plates of the frame, the flange 16 of the pan being secured directly to the plates by means of bolts 18 that are received in the bolt holes 17. The hangers are arranged in the pan 90 and the head plates of the hangers are arranged in contact with the under side of the flange 16 and directly secured thereto by means of the bolts 18. One of the functions 95 of the pan is to partially encase a gas-burner in a manner to assist in controlling heat, as in a combustion chamber or fire-box. The pan has a depth approximating one-half the length of the leg member of the stove. A gas-burner is provided which is composed of 100 105 110

piping and fittings and comprises a T head 19, nipples 20 and 21 connected to opposite sides of the head, elbows 22 and 23 connected to the nipples respectively, and tubular burners or pipes 24 and 25 connected to the elbows respectively. The burner pipes extend through the hangers 10 and 11 respectively and each pipe has a cap 26 secured thereon adjacent to the outer side of the hanger, being near to the wall 15 of the pan. A suitable gas-mixer 27 is made use of which has a neck 28 that is screwed into the T-head 19, the neck being slightly tapered and inserted through a hole 29 in the wall of the pan and also through the hanger member 12, the tapered neck being fitted closely in the holes, so as to tend to draw the caps 26 close to the hangers 10 and 11, for holding the burner tightly in place. A jet nozzle 30 is arranged in connection with the mixer, as is customary and has a gas-cock 31 connected thereto, integrally or otherwise, the gas-cock having a neck 32 adapted to have a gas-supplying hose or pipe connected thereto. Preferably the under side of the mixer has a boss thereon to which a bracket arm 33 is secured which has an upward extending relatively angular arm 35 thereon that is secured to and supports the neck 32. The burner pipes have each a row of jet-holes 36 on one upper side portion and a separate row of jet-holes 36' in the opposite upper side portion thereof. The burners are spaced a considerable distance apart so that the flames therefrom shall be directed to the bottom of the wash-boiler nearly over the whole surface thereof but more directly to those portions adjacent to the longer sides of the wash-boiler.

The pan or combustion chamber structure prevents wind currents from interfering with proper combustion when the stove is used out-doors, but to admit sufficient atmospheric air to promote proper combustion the bottom 14 of the pan has a suitable number of apertures 37 therein, through which water may drain in case of unintentional spilling of water into the pan.

For the purpose of venting the combustion chamber, when a wash-boiler is on the stove a suitable number of spacing blocks 38 and 38' are secured to the tops of the top plates 1 and 2 of the frame, similar spacing blocks 39 and 39' being secured upon the transverse top plates 3 and 4 respectively to directly support the bottom of the wash-boiler and afford channels beneath said bottom to induce circulation of heated air whereby to obtain high efficiency in operation of the gas-burners. The spacing blocks may be secured in place by means of rivets 40, or may be secured by welding if desired.

In practical use the stove is easily carried by one person, even though not a strong

woman, and is readily placed where desired, a gas-supplying hose or pipe being connected with the gas-cock, the latter to be opened when ready and the gas escaping from the burners immediately ignited. Atmospheric air becomes mixed with the gas in the single mixer and therefore the same quality of fuel gas is conducted to both of the burners. A wash-boiler is to be placed upon the spacing blocks of the frame for boiling water for washing or other purposes. The position of the wash-boiler on the stove is indicated by broken lines in Fig. 3, it being designed that the heat shall induce upward currents of water adjacent to the longer sides of the wash-boiler, downward return currents occurring between the up-currents, so that there shall be considerable velocity of current to assist in cleansing garments or fabrics which may be placed in the boiling water. The stove may be found useful for heating other vessels that can be suitably placed on the stove.

What is claimed as new is:

1. A gas-burning laundry stove comprising an oblong frame, legs secured to the frame, a pan having an inwardly-extending flange arranged against the under side of the frame, bolts securing said flange to the frame and being accessible inside the pan, hangers having members arranged in the pan and connected to said bolts, and burners in the pan supported by said hangers.

2. In a gas-burning laundry stove, the combination of an oblong frame, legs secured to the corners of the frame, a pan comprising a bottom and a side wall, the wall having an inwardly-extending flange on its upper edge engaging the bottom of said frame, bolts securing said flange to said frame, hangers arranged in said pan and secured to said flange, a T-head and burner pipes connected therewith and arranged in the pan, the pipes being supported by two of the hangers respectively, a gas-mixer connected with the T-head and supported by another one of the hangers, and a gas-cock connected with the gas-mixer.

3. In a gas-burning laundry stove, the combination of an oblong frame, legs secured to the corners of the frame, a pan having an inwardly-extending flange thereon secured to the under side of the frame, the pan having also an aperture in one end thereof, two hangers spaced apart in the pan adjacent to the opposite end thereof and secured to said frame, and a gas-burner comprising a conduit supported in said aperture, two burner pipes connected with said conduit and extending through said hangers respectively for support, and two caps secured to the ends of said pipes respectively and engaging said hangers and the inner side of the adjacent end of said pan.

4. In a gas-burning laundry stove, the

combination of an oblong frame comprising a flat top plate and a facing plate extending downward from the outer edge of the top plate, legs secured to the inner side of said facing plate and seated against the under side of said top plate, a pan comprising an oblong perforated bottom and a wall thereon, said wall having a flange at its top extending inwardly against the under side of said frame top plate and being removably secured thereto, hangers having head plates removably secured to the under side of said

flange, and a gas burner arranged in said pan and comprising a conduit supported in the front end of the pan and burner pipes secured to and supported by said hangers, a gas-mixer connected with said conduit, a gas-cock connected with the gas-mixer and having an inlet neck, and a bracket secured to the gas-mixer and to said neck. 20

In testimony whereof, I affix my signature on the 30th day of July 1924.

BURR R. SKINNER.
